[57] CLAIM

The ornamental design for a crib footboard, as shown and described.

DESCRIPTION

FIG. 1 is a front elevation view of a crib footboard according to the invention;

FIG. 2 is a side elevation view thereof;

FIG. 3 is a sectional view thereof taken along the plane of line 3—3 in FIG. 1;

FIG. 4 is a sectional view taken along the plane of line 4—4 in FIG. 1;

FIG. 5 is a sectional view taken along the plane of line 5—5 in FIG. 1; and

FIG. 6 is a sectional view taken along the plane of line 6—6 in FIG. 1.

The rear surface of the crib footboard is conventional in appearance.

The crib footboard is characterized by the distinctive configurations and ornamental grooves of the top and bottom cross members as best shown in FIGS. 1, 3 and 6.
